COVER FOR CAMERA CASES OR SIMILAR ARTICLE

Samuel C. Roth, Allentown, Pa.

Application August 27, 1953, Serial No. 26,603

Term of patent 3½ years

(Cl. D61—1)

FIG.1.

FIG.2.

FIG.3.

Fig. 1 is a perspective view of a cover for camera cases or similar article, taken from the top and rear.

Fig. 2 is an elevational view thereof, taken from the side.

Fig. 3 is a perspective view thereof, taken from the top and front.

The dominant feature of my design resides in the portions shown in full lines.

I claim:

The ornamental design for a cover for camera cases or similar article as shown and described.
